TENSIONED METAL WHEEL.
APPLICATION FILED MAY 13, 1918.

Patented Apr. 25, 1922.

2 SHEETS—SHEET 2.

UNITED STATES PATENT OFFICE.

HENRY J. FOSTER, OF CLEVELAND, OHIO, ASSIGNOR TO THE HYDRAULIC PRESSED STEEL COMPANY, OF CLEVELAND, OHIO, A CORPORATION OF OHIO.

TENSIONED METAL WHEEL.

1,414,013.

Specification of Letters Patent. Patented Apr. 25, 1922.

Application filed May 13, 1918. Serial No. 234,108.

To all whom it may concern:

Be it known that I, HENRY J. FOSTER, a citizen of the United States, residing at Cleveland, in the county of Cuyahoga and 5 State of Ohio, have invented a certain new and useful Improvement in Tensioned Metal Wheels, of which the following is a full, clear, and exact description, reference being had to the accompanying drawings.

10 This invention relates generally to wheels and more particularly to a sheet metal wheel designed for use upon automobiles and motor vehicles.

The object of the invention is to provide 15 a simple and inexpensive metal wheel capable of carrying its load and withstanding lateral strain, and a still further object is to provide a sheet metal wheel in which the parts will be tensioned in the course of 20 manufacture and whereby a tension or suspension wheel will be provided thereby permitting the use of lighter material in the make-up of a wheel.

Another object of the invention is to provide 25 a sheet metal wheel which can be used in connection with any and all of the present types of demountable tire-carrying rims and means for fastening the same.

A still further object is to provide a sheet 30 metal wheel of such construction that great economies can be practiced, both in the use of material and assemblage of the device.

With these objects in view the invention consists of the novel features of construction 35 and combination all of which will be fully described hereinafter and set forth in the appended claims.

In the drawings forming part hereof Fig. 1 is a perspective view of a sheet metal wheel 40 embodying my invention; Fig. 2 is a vertical longitudinal section showing one-half of the wheel body; Fig. 3 is a side elevation of a wheel embodying my invention; Fig. 4 is a detail sectional view showing a slight modification; Fig. 5 is a view illustrating the 45 relative position of the spokes and felly band prior to the tensioning and fastening operation; Fig. 6 is a detail edge view of the dual spokes; Fig. 7 is a detail perspective view of the same; Fig. 8 is a detail perspective view of the tensioning and fastening bolt; and Fig. 9 shows the blank of one of the dual spokes.

In the practical embodiment of my invention I employ a hub A which so far as the

interior is concerned may be of any desired construction. Upon the exterior, the hub is provided with an annular flange B, adjacent the inner end, and also an annular flange C, adjacent the outer end, and to these flanges B and C are connected the ends of the dual spokes D; each spoke comprising an inner portion D¹, an outer portion D², and an intermediate portion D³; and at their extreme ends, the spokes are bent in reverse 60 directions as indicated at D⁴ in order to provide suitable rests or foot pieces for said spokes.

The dual spoke is punched from a sheet of metal in the form shown in Fig. 9 and it 70 will be noted that the ends thereof are slightly enlarged and tapered as indicated at D⁵ so that when all of the spokes are properly assembled and connected they provide a nave or central portion, the oblique 75 edges of each tapered end contacting with the oblique edges of the next adjacent one.

These spoke ends are rigidly connected to the hub flanges B and C by riveting or 80 spot welding, and it will be noted by reference to Fig. 2 that the front and rear sections of the dual spokes are in line with each other. If desired the spokes can be slightly rounded as indicated at D⁶ in order to impart a more ornamental finish. In connection 85 with the sheet metal spokes which are rigidly connected to the hub flanges as previously described, I employ a sheet metal felly E, preferably of the box type and constructed substantially the same as the box 90 felly shown, described and claimed in my application of even date herewith Serial No. 234,016. The central portions of the dual spokes or the ends of the front and rear sections are rigidly connected to the felly E 95 by means of bolts F having large heads G. This bolt head is of such size and shape as to fit exactly into the bend of the dual spoke, the edges of said head which contact with the metal spoke being rounded slightly or given a short radius in order to avoid the contact of a sharp edge with the metal spoke. The threaded shank of the bolt is passed through the bottom of the box felly and a 100 nut H screwed thereon.

By reference to Fig. 5 it will be noted that the dual spoke is of such length that there is a slight space or clearance between the spoke end and the bottom of the box felly and when the nut is tightened the head of the 110

bolt is drawn forcibly toward the box felly carrying with it the central portion D^3 of the dual spoke, and the movement is continued until the intermediate portion of the 5 spoke is brought into binding contact with the bottom of the box felly as most clearly shown in Figs. 1 and 3, and then the end of bolt can be headed down or the nut locked in any suitable manner to prevent any possible 10 loosening of these parts.

When the bolt is drawn up as previously described and the intermediate portion of the spoke drawn up into contact with the box felly the front and rear portions of the 15 dual spoke will be placed under considerable tension inasmuch as the opposite ends of said spoke have been rigidly secured to the hub flanges. Each one of the dual spokes is tensioned and connected to the box felly and the 20 completed wheel will therefore be a tension or suspension wheel comprising a light box felly, sheet metal spokes each formed of a single piece of sheet metal connected at its front and rear ends to front and rear hub 25 flanges and properly tensioned while being connected to the box felly at their intermediate points.

If desired inner and outer rings I and K can be arranged upon the hub and secured 30 by means of bolts L passing through the said rings, spoke ends and hub flanges; and a brake drum M can also be connected at the same time if desired as shown in Fig. 2. Any suitable form of hub cap N may be employed and any suitable form of felly band 35 O may be arranged upon the box felly for the purpose of carrying the demountable tire carrying rim P. If the construction of the box felly is suitable, a separate felly band 40 may be dispensed with.

Various types of rim fastening devices may be employed, and in the present instance we have shown the clamping wedge Q arranged upon the transverse bolt R and 45 secured in position by means of the nut S.

A wheel constructed as herein shown and described is very economical from the standpoint of material and manufacture and when completed provides a strong and durable sheet metal wheel of neat and attractive appearance and a wheel of the tension or suspension type.

Furthermore should one or more of the 50 spokes become bent or distorted they can be straightened and restored to their original shape and position and if one or more spokes

should become broken it is possible to remove the broken spoke or spokes and insert new ones; and this repair or replacement can be done by an ordinary mechanic, and it will, 60 therefore, not be necessary to return the wheel to the place of original manufacture for such repairs.

Having thus described my invention, what I claim is:—

65

1. A wheel comprising a felly, a hub having flanges, and dual spokes, the ends of said spokes being rigidly secured to said hub flanges, and radially movable members each having an enlarged portion adapted to contact with the intermediate portion of a said dual spoke and move the same into binding contact with said felly.

70

2. A wheel comprising a felly, a hub having radial flanges, and spokes consisting each of inner, outer and intermediate portions, the free ends of said inner and outer portions being rigidly secured to said hub flanges, the intermediate portions of said spokes being spaced slightly from said felly 75 and means for moving said intermediate portions into contact with said felly and permanently fastening said parts together.

80

3. A wheel comprising a felly, a hub having flanges, and a plurality of spokes, each 85 spoke bent upon itself providing inner and outer portions and an intermediate portion, the free ends of said inner and outer portions being rigidly secured to said hub flanges, the intermediate portions being 90 spaced from said felly, and bolts passing through said intermediate portions and felly, said bolts having enlarged heads adapted to engage said intermediate portions and nuts secured upon the ends of said bolts 95 and within the felly.

100

4. A wheel comprising a hub having radial flanges, a box felly, and spokes formed each of a single piece of sheet metal bent to provide a dual spoke, the free ends of said 105 spokes being tapered and secured to the hub flanges, the tapered ends of said spokes contacting, bolts passing through the intermediate portions of the dual spokes, said bolts having enlarged heads, the edges of which 110 are rounded, nuts within the felly and upon said bolts, and hub rings and bolts all arranged as set forth.

105

In testimony whereof, I hereunto affix my signature.

HENRY J. FOSTER.
